UNITED STATES PATENT OFFICE.

REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS.

SHADE-SUPPORTING LAMP-SOCKET.

1,206,084.

Specification of Letters Patent. Patented Nov. 28, 1916.

Application filed March 1, 1912. Serial No. 681,002.

To all whom it may concern:

Be it known that I, REUBEN B. BENJAMIN, a citizen of the United States, residing at Chicago, in the county of Cook and State of Illinois, have invented new and useful Improvements in Shade-Supporting Lamp-Sockets, of which the following is a full, clear, concise, and exact description, reference being had to the accompanying drawing, forming a part of this specification.

My invention pertains to electric-lamp-receiving sockets, and shade supporting devices for use in connection therewith; and my invention particularly relates to electric-lamp sockets of the kind which are known in the art as pendant sockets; *i. e.*, sockets which are intended to be supported from a hanging cord.

Among others, it is an object of my invention to simplify, and improve upon generally, the construction of pendant sockets.

It is a further object of my invention to provide an electric-lamp socket to which a shade support may be attached in varying positions, according to the nature of the lamp employed in the socket. And it is a still further object of my invention to provide a shade support, which may be safely and conveniently employed in connection with sockets of varying sizes and characters, and to improve upon the construction of shade supporting devices generally.

A pendant socket and shade supporting device, constructed in accordance with my invention are described in the following specification and shown in the accompanying drawings. It is to be understood, however, that the invention may be embodied in other constructions than that shown, within the scope of the appended claims, and that, although the form of shade supporting device which I have described has particular advantages when used in connection with the form of pendant socket which I have shown, nevertheless, each of these devices has important uses in other connections.

In the drawings: Figure 1 is a vertical section taken through the socket and shade supporting device constructed in accordance with my invention, the section being taken on the line 1-1 of Fig. 2; Fig. 2 is a plan of the same on an enlarged scale, the terminal-protecting and cord-gripping bushing

being, however, removed in order to display the binding terminals; Fig. 3 is a side elevation of the same; a portion of the shade being broken away so as to display the means for connecting the shade to its supporting device; Fig. 4 is a vertical section taken on the line 4-4 of Fig. 2 looking in the direction of the arrows; Fig. 5 is a perspective view of one of the clamping members of the shade supporting device; Fig. 6 is a detail section on the line 6-6 of Fig. 5; Fig. 7 is a perspective detail view of one of the shade supporting stirrups; and Fig. 8 is a perspective view of the top portion of the shade.

Referring now to the drawings, and particularly to Figs. 1-4 thereof, 10 indicates an insulating body member having formed in the lower end thereof a lamp-base receiving chamber 11, the bottom of this chamber being formed with a central boss 12. A threaded lamp receiving contact 13 is mounted in the chamber 11, and is secured in position by means of screws 14 and 15, passing vertically through the body member 10. Of these screws, the screw 14 passes downwardly through the body member 10 and enters the threaded contact 13, and the screw 15 passes upward through the body member 10, and enters a binding plate 16 which carries a binding screw 17. The center lamp-terminal-engaging contact 18 lies upon the boss 12 and is provided with a lug 19, which enters a small recess 20, formed for that purpose in the bottom of the chamber 11. A screw 21 passes upwardly through the lug 19 of the center contact 18 and through the body member 10, entering a binding plate 22, which, like the binding plate 16, lies in a suitable depression in the top part of the body member. The binding plate 22 is provided with a binding screw 23. It will be seen from the above that current led to the binding screw 17 will pass through the screw 15 to the threaded contact 13, and thence through the lamp to the center contact 18, and, through the screw 21, back to the binding screw 23.

The upper end of the body member 10 is provided with an annular internally screw threaded shoulder 24, which is adapted to receive an externally screw threaded insulating bushing 25, preferably formed of hard rubber or some similar material. The bushing 25 is provided with a central aperture 110

26, through which the lead wires 27 and 28 may be brought to the binding screws 17 and 23, respectively. The top end of the body member 10 is further provided with 5 a central boss or projection 29, of frusto-conical shape, the top edge of which operates with the bottom edge of the aperture 26 to form a clamping device for gripping the lead wires and preventing them 10 from being detached from the binding terminals.

In connecting up the socket, the bushing 25 is passed over the lead wires, and the ends of the latter are then secured beneath the 15 binding screws 17 and 23. When this has been done, the bushing 25 is secured into the annular shoulder 24. It will be seen that the insertion of the bushing 25 into the annular shoulder 24 will result in the lead 20 wires being firmly gripped between the lower edge of the opening 26 of the bushing and the upper edge of the boss 29 of the body member, the bushing 25 thus serving at once as a cap for protecting the binding 25 terminals and as a clamping device for the leading in wires. The effect of the construction is that the weight of the lamp, the shade and the socket itself, is taken by the bushing 25, which is well able to withstand 30 the strain, and the binding terminals are relieved from such weight. The bushing 25 is hollowed out at 30, so as to provide sufficient room for the lead wires to be brought to the binding terminals, and at the same 35 time, allow sufficient depth of the bushing to permit of a firm threaded engagement. The bushing and the shoulder 24 are thus permitted to be of reasonably small dimensions, whereby the socket is of minimum 40 weight and of neat appearance.

At its lower end, the body member 10 is formed with an outwardly projecting shoulder 31, which is adapted to sustain the shade 45 supporting device in such a position that the shade will be properly located with respect to a particular variety of lamp—in the construction shown, a 100 watt lamp. The body member 10 is also reduced somewhat, at its upper end, so as to form a second 50 shoulder 32 adapted to support the shade supporting device (see dotted lines Fig. 3), when a smaller lamp is being employed. This construction permits the shade to be 55 properly located with respect to the lamp, regardless of whether a large or a small lamp is employed, which is an advantage of considerable importance.

The shade holder consists of two arcuate 60 bands 33 each of which is somewhat less than a semi-circle. The length of the bands 33 is such that their ends will be spaced apart when the bands are fitted around the body member 10; and each of the bands has its ends bent out so as to form lugs 34. In 65 conjunction with these bands, stirrups 35 are

employed; the upturned ends 36 of which extend upward through suitably positioned slots 37 formed in an inturned flange 38, which is provided at the upper end of the shade 39. Clamping screws 40 pass through 70 apertures in the lugs 34 of the bands 33 and in the ends 36 of the stirrups 35, these screws being buried over at their ends to prevent withdrawal. Threaded upon the clamping screws 46, are nuts 41 arranged so as to 75 clamp the adjacent lugs 34 between them and the heads of the clamping screws 40. It will be seen that by tightening the nuts 41 upon the clamping screws 40, the lugs 34 will be moved toward each other and the bands 33 80 will consequently be tightened upon the body member. When it is desired to use a small lamp in the socket, instead of the lamp shown, the nuts 41 are loosened, whereby the bands 33 become loose. When this has 85 been done, the shade supporting device and shade may be moved upward upon the body member 10 to engage the shoulder 32. The nuts 41 may then be again tightened to 90 clamp the shade supporting device and shade 95 in the new position.

In order to permit the shade supporting device to be employed in connection with sockets of other kinds, as, for instance, in connection with metallic sockets of the kind 95 in which a bead is provided adjacent the outer end of the socket, I form, in each of the bands 33, an arc-shaped hollow bead 42. The beads 42 are formed upon a curve, which is a part of a circle drawn about a center 100 which is intermediate the inner ends of the lugs 34, the curvature of the beads 42 being therefore of a greater convexity than that of the bands 33. When the shade supporting device is employed in connection with a 105 socket of the kind in which a bead is provided adjacent the outer end, the hollow bead 42 of the shade supporting device fits over the bead of the socket, and, when the bands 33 are clamped together, the shade 110 supporting device becomes firmly secured to the socket so as to be safely supported thereby.

Having thus described my invention, what I claim as new and desire to secure by Letters Patent, is:

1. A pendant electric lamp socket comprising, in combination, an integral insulating base having a lamp engaging socket, lamp-terminal-engaging contacts mounted 120 on the front side of said base in said socket, binding terminals mounted on the rear side of said base, a one-piece insulating cap removably secured directly to said base and covering said binding terminals, said base 125 and said cap being formed so as to grip the lead wires between them when said cap is secured directly to said base, said cap having a single opening therethrough for the leads from said terminals.

2. A pendant electric lamp socket comprising, in combination, a one-piece integral insulating base having an internally screw-threaded shoulder at its rear side and 5 having an internally threaded lamp-engaging socket in its front side, lamp-terminal-engaging contacts mounted on the front side of said base, binding terminals mounted on the rear side of said base, and a one-piece 10 screw-threaded insulating bushing adapted to screw into the shoulder of said base, so as to cover said binding terminals, said base and said bushing being formed so as to grip the lead wires between them when said bushing is screwed into said shoulder, said bushing having a single opening therethrough for the leads from said terminals. 15
3. A pendant electric lamp socket comprising, in combination, a one-piece integral insulating base having a projection at the 20 rear side thereof and having an internally threaded lamp-engaging socket in its front side, lamp-terminal-engaging contacts mounted on the front side of said base in said socket, binding terminals mounted on the rear side of said base, and a one-piece cap having screw-threaded connection with said base and covering said binding terminals, said cap having a single aperture 25 therein for the passage of lead wires therethrough, such aperture being located with respect to the projection of said base so that the lead wires will be clamped between the edge of such aperture and said projection. 30
4. A pendant electric lamp socket comprising, in combination, a one-piece integral insulating base having an internally screw-threaded shoulder at its rear side, a lamp-engaging socket at its front side and also 35 having a projection at its rear side, lamp-terminal-engaging contacts mounted on the front side of said base, binding terminals mounted on the rear side of said base, and a one-piece screw-threaded bushing adapted 40 to be screwed into said shoulder so as to cover said binding terminals, said bushing 45
- having a single aperture for permitting the passage of lead wires therethrough, such aperture being positioned with respect to said projection so that the lead wires will be clamped between said projection and the edge of such aperture. 50
5. A pendant electric lamp socket comprising, in combination, a one-piece insulating base having an internally screw-threaded shoulder at the rear side thereof and also having a frusto-conical projection at the rear side thereof, binding terminals mounted on the rear side of said base, and a one-piece screw-threaded bushing adapted to be 55 screwed into said shoulder so as to cover said binding terminals, said bushing having an aperture for permitting the passage of lead wires therethrough, such aperture being positioned with respect to said projection so that the lead wires will be clamped between said projection and the edge of such aperture. 60
6. A pendant electric lamp socket comprising, in combination, a one-piece insulating base having an internally screw-threaded shoulder at the rear side thereof and also having a projection at the rear side thereof, binding terminals mounted on the rear side of said base, and a one-piece screw-threaded 65 insulating bushing adapted to be screwed into said shoulder and having an aperture for the passage of lead wires therethrough, such aperture being located with respect to said projection so that the lead wires will be clamped between said projection and the edge of such aperture, and said bushing being hollowed out at its lower side, for the 70 purposes set forth. 75
- In witness whereof, I have hereunto subscribed my name in the presence of two witnesses. 80
- REUBEN B. BENJAMIN.
- Witnesses:
- MABEL REYNOLDS,
C. E. KANE.

It is hereby certified that in Letters Patent No. 1,206,084, granted November 28, 1916, upon the application of Reuben B. Benjamin, of Chicago, Illinois, for an improvement in "Shade-Supporting Lamp-Sockets," an error appears in the printed specification requiring correction as follows: Page 2, line 128, claim 1, strike out the word "directly"; and that the said Letters Patent should be read with this correction therein that the same may conform to the record of the case in the Patent Office.

Signed and sealed this 23d day of January, A. D., 1917.

[SEAL.]

E. W. H. CLAY,
Acting Commissioner of Patents.
